FLUORESCENT TUBE SUPPORTING BRACKET

Herman Hassinger, Philadelphia, Pa., assignor to Herman Hassinger, Incorporated, Philadelphia, Pa.

Application May 26, 1954, Serial No. 30,663

Term of patent 7 years

(Cl. D48—23)

To all whom it may concern:

Be it known that I, Herman Hassinger, a citizen of the United States, residing at Philadelphia, State of Pennsylvania, have invented a new, original, and ornamental Design for Fluorescent Tube Supporting Brackets, of which the following is a specification, reference being had to the accompanying drawing, forming a part hereof.

Fig. 1 is a front elevational view of a fluorescent tube supporting bracket showing my new design;

Fig. 2 is a rear elevational view;
Fig. 3 is a top plan view; and
Fig. 4 is an end elevational view.

I claim:
The ornamental design for a fluorescent tube supporting bracket, as shown.
